(57) **CLAIM**

The ornamental design for a fractal vise jaw as shown and described.

DESCRIPTION

FIG. 1 is an isometric view of a fractal vise jaw. FIG. 2 is a top plan view of the fractal vise jaw of FIG. 1. FIG. 3 is a bottom view of the fractal vise jaw of FIG. 1. FIG. 4 is front view of the fractal vise jaw of FIG. 1. FIG. 5 a rear view of the fractal vise jaw of FIG. 1. FIG. 6 is a left side view of the fractal vise jaw of FIG. 1; and, FIG. 7 is a right side view of the fractal vise jaw of FIG. 1. Portions of FIGS. 1 through 7 are shown in broken lines and dash-dot-dash boundary lines illustrating portions of the article that form no part of the claimed design. The dash-dot-dot-dash lines in FIGS. 1 and 5 are directed to environment and form no part of the claimed design.
